UNITED STATES PATENT OFFICE

FRED R. WEISS, OF FRENCHTOWN, NEW JERSEY

DESIGN FOR A VEHICLE SIGNAL HOUSING

Application filed March 23, 1929. Serial No. 30,601. Term of patent 3½ years.

To all whom it may concern:

Be it known that I, FRED R. WEISS, citizen of the United States, residing at Frenchtown, in the county of Hunterdon and State of New Jersey, have invented a new, original, and ornamental Design for a Vehicle Signal Housing, of which the following is a specification, reference being had to the accompanying drawing, forming part thereof.

I claim:

The ornamental design for a vehicle signal housing as shown.

FRED R. WEISS.
